UNITED STATES PATENT OFFICE

2,266,726

WINDING MACHINE

Edward J. Abbott, Wilton, N. H., assignor to
 Abbott Machine Company, Wilton, N. H., a
 corporation of New Hampshire

Application June 6, 1939, Serial No. 277,618

27 Claims. (Cl. 242—32)

This invention relates to winding machines of the traveling multiple-unit type and more particularly to machines adapted to wind yarn packages in which the winding yarn is laid in axially advancing conical layers, a typical instance of such package being the "filling wound" package. My copending application Serial No. 576,978, filed November 24, 1931, now Patent No. 2,160,810, discloses and claims the combination of a plurality of flexibly connected winding units each adapted to carry a winding package core, means for moving the units in a path of elongated shape including a straight portion of substantial length, means for rotating the several packages during their travel in said straight portion of the path, and means operative during the winding to distribute the strand in conical layers of less length than the finished package length, and means for shifting the ranges of strand traverse axially of the package.

The United States reissue Patent No. 18,310 of Edward J. Abbott and William G. Abbott, Jr., discloses a traveling multiple-unit winding machine in which the rotation of the winding packages and the operation of the traverse mechanisms on the traveling winding units is brought about by mechanical connections, more particularly long non-traveling tractor rolls, common to a number of the traveling units. In that reissue patent the winding packages are of the typical cross-wound cheese construction and grow radially as they travel along the tractor rolls. On the other hand, winding packages of the type produced by my copending application Serial No. 576,978 in which the packages grow axially are not adapted to receive their winding rotation by frictional contact with the long tractor rolls of the said reissue patent and my copending application Serial No. 576,978 drives the winding packages and their traverse mechanisms by providing each winding unit with an individual electric motor.

An object of this invention is to improve traveling-unit winding machines of the general type disclosed in said reissue patent and copending application in such manner as to secure the production of axially growing packages, particularly the filling wound type of package, on traveling winding units by means of mechanical driving connections common to a number of the traveling units. Preferred examples of the invention provide for the production of this type of package on a winding machine having the general frame construction and non-traveling tractor roll construction of the said reissue patent, thus permit-

ting the production of this filling wound type of package on traveling winding machines having the general organization of the traveling spindle winding machines now in common use for the production of the typical cross-wound cheese.

Further objects of the invention are to improve and simplify the driving connections for the winding packages and traverse mechanisms of traveling unit winding machines.

10 Other objects of invention and features of advantage and utility will be apparent from this specification and its drawings, wherein the invention is explained by way of example.

The winding machine is provided with a frame 15 and traveling-unit guideway such as is disclosed in the said reissue patent and copending application, the guideway having relatively long straight side portions and circular ends, and in the forms shown in Figs. 1 to 9, inclusive, is provided with 20 non-traveling tractor rolls 50 constructed and driven in the manner disclosed in the said reissue patent. Each form of the winding machine is provided with a large number of individual flexibly connected winding units (for example one 25 hundred) moved in a continuous manner around the machine by any suitable driving chains such as those disclosed in said reissue patent and copending application.

In the drawings:

30 Fig. 1 is a vertical sectional view through one side of the guideway and through the corresponding tractor roll of the machine, showing one of the traveling winding units;

35 Fig. 2 is a fragmentary plan view of the mechanism of Fig. 1;

Fig. 3 is a front elevation of the upper portion of the winding unit of Figs. 1 and 2;

40 Fig. 4 is a view similar to Fig. 1 (but facing in the opposite direction) showing a modified form of winding unit partially in vertical section;

Fig. 5 is a plan view, partially in horizontal section, of the mechanism of Fig. 4;

45 Fig. 6 is a vertical section on the line 6—6 of Fig. 5, showing particularly the means for guiding the yarn onto the winding package;

Fig. 7 is a view similar to Fig. 1, showing a further modified form of traveling unit;

Fig. 8 is a plan view of the mechanism of Fig. 7;

50 Fig. 9 is a vertical section on the line 9—9 of Fig. 8;

Fig. 10 is a vertical section through the guideway and package driving mechanism of a further modified form of the machine showing in side elevation one of the winding units and yarn-travers-

ing mechanism common to the several units of the machine; and

Fig. 11 is a front elevation of a fragment of one side of the machine of Fig. 10 with parts broken away and with all of the winding units except one omitted for clarity of illustration, and showing successive positions of the winding package of a traveling winding unit.

In each of the several embodiments of the invention, similar parts being designated by the same reference numeral, each winding unit is provided with a vertical upright frame element 20 having integral therewith at its upper end a horizontal portion 21 on which are mounted a pair of flanged vertical rollers 23 running on the upper edge of the upper guide rail 27 and a horizontal roll 28 running on the inner face of the guide rail 27. At its lower end the vertical frame member 20 is guided on the lower guide rail 30 by the roller 31 and a pin 32 projecting downwardly from an inwardly extending bracket 33. The vertical frame element 20 of each winding unit is also provided near its lower end with a bracket 35 carrying any suitable supply package holder such as a pin, peg or the like to receive and hold the unwinding supply package which is indicated at S. Each winding unit is flexibly connected to the driving chain 37 by a link 38 (Figs. 1 and 2), the chain 37 corresponding to the chain 30 of the said reissue patent and these parts being omitted from the subsequent figures of the application for clarity of illustrations.

Referring to Figs. 1, 2 and 3, the winding unit of this invention includes a spindle 40 rotatably mounted in a bearing 41 and suitably shaped to interfit with and rotate the winding package core 43. A shaft 45 rotatably mounted in a further bearing 46 carries a thick cork tire 51 frictionally engaging the tractor roll 50 and a beveled gear 55 meshing with a similar beveled gear 56 on the spindle 40. By this means the spindle 40 and the package core 43 are rotated as the winding unit travels along the tractor roll 50. The traverse mechanism is carried on a bracket 60 mounted on a slideway 61 which constitutes a horizontal extension of the head portion of the unit. An arm 63 depending from the bracket 60 carries a suitable yarn guide such for example as the pigtail 64. A conical roll 66 is rotatably mounted on an inclined horizontal extension 67 of the bracket 60 in position for the conical surface of the roll to bear against the axially growing face of the winding package P. A spiral groove 69 in roll 66 serves as a traversing yarn guide, receiving the yarn Y from the pigtail 64 and traversing it back and forth across the axially growing face of the package P. The conical roll 66 is driven frictionally by contact with the yarn of the package and, as the package grows, the bracket 60 and the traverse mechanism carried thereby are progressively shifted to the right in Figs. 1 and 2 parallel with the surface of the winding package by the pressure of the growing yarn against the roll 66. In this way the package is built up of successive spiral layers of yarn from the left to the right in Figs. 1 and 2, Fig. 2 showing the package about two-thirds completed.

Any suitable spring or weight, not shown, may be employed if desired to urge the traverse assembly to the left in Figs. 1 and 2, to increase the pressure between the conical roll 66 and the growing package, and following the removal of the full package and substitution of a new core 75

to return the traverse assembly to the starting position at the left end of the new core.

In the modified form of winding unit of Figs. 4 to 6, inclusive, the spindle 40 rotatably mounted in bearings 41, is driven through the bevel gears 56 and 55 from a cross shaft 45 which carries a cork tire 51 contacting with and frictionally driven by the tractor roll 50. The yarn Y from the supply package S runs up through the pigtail 64, over a yarn guide 71 and thence downwardly onto the growing conical surface of the winding package P.

The yarn guide 71 is supported on a reciprocating traverse bar 72 by a bifurcated frame 73. A friction contact disk 75 mounted on the traverse bar 72 between the two legs of the frame 73 is internally threaded to engage half threads 72^a on the traverse bar 72. The traverse bar 72 is given a reciprocating motion equal in length to the length of a conical layer of the yarn on the winding package by a heart-shaped cam 78 which engages the follower 79 at the right end of the traverse bar. The heart-shaped cam 78 is driven from the cross shaft 45 by skew gearing 82, 83. As the conical nose of the winding package P grows toward the left and the friction wheel 75 comes in contact therewith, the friction wheel is rotated by the winding package sufficiently to move the traverse assembly and yarn guide 71 slightly to the left, thus shifting the range of traverse progressively as the winding package grows. When the winding package is completed and removed the traverse assembly may be restored to the right in Figs. 4 and 5 by pressing the friction wheel 75 in a direction to disengage its internal threads from the half threads 72^a and sliding the traverse assembly to the right.

In the modified form of the winding unit of Figs. 7 to 9, inclusive, the spindle 40 mounted in bearing 41 carries a bevel wheel provided with a thick facing of cork 51^a at its inner end, the spindle being so inclined that the cork facing 51^a frictionally engages the tractor roll 50. The yarn guide and traverse assembly are similar to those of Figs. 4 to 6, inclusive. A second bevel wheel provided with a thick cork facing 51^b contacts with the tractor roll 50 to drive a cam shaft 90 carrying a grooved cam 91 which in turn drives the follower 79 at the inner end of the traverse bar 72. The traverse assembly can be restored to its innermost position for the starting of a new package in the same manner as in the device of Figs. 4 to 6.

In the modified form of device of Figs. 10 and 11, the upper part of the winding unit is provided with bearings 41^a for a vertically disposed spindle 40 on which is mounted a pulley 51^c between the bearings 41^a.

Located approximately above the upper rail 27 along each straight portion of the track of the machine, and backed by flanged vertical rollers 100 there is provided a fast moving belt 101 driven by any suitable means and contacting with the pulleys 51^c of the winding units. In this manner the spindle of each winding unit is driven at a high speed during the travel of the winding unit along the straight portion of track extending along one side of this machine. The driving is then stopped as the pulley 51^c leaves the belt in passing around the semi-circular end of the machine and commences again as the pulley comes in contact with the other belt 101 at the opposite straight side of the machine.

On the winding unit the yarn Y from the sup-

ply package S passes upwardly through any suitable tension device T and through a guide-eye 103 on a vertical extension of the head of the winding unit.

For traversing the yarn on the winding core there is provided a long non-traveling rod or wire 105, extending along the straight portion of the track, the yarn from the guide-eye 103 of each winding unit on the straight portion of track extending down under this rod 105 and thence onto the winding package.

The rod 105 has an inclination such that as the winding units travel from the right to the left in Fig. 11, the rod 105 will position the yarn adjacent to the base of the winding core as the unit begins to travel along the straight portion of the track and will progressively allow the yarn to wind higher on the winding core until when the left end of the straight portion of track is reached, the yarn is winding on the last or outermost conical layer adjacent to the tip of the winding cone.

In order to distribute the yarn with a relatively short traverse across the growing conical nose of the package each rod 105 is given a short up and down motion. For this purpose the rods 105 on both sides of the machine are suspended on rocker arms 106 which are rocked about a central rocker shaft 107 by crank arms 108, cam followers 109 and heart-shaped cams 110 driven by suitable gearing 111, 112 from a central drive shaft 113.

By this means each winding unit while traversing the straight portion of track at one side of the machine winds a complete package, the two components of the traverse motion of the yarn being supplied by the gradual upward inclination of the rod 105 and the short continuous rocking motion of rod 105.

I claim:

1. A traveling unit winding machine having therein a plurality of flexibly connected winding units each adapted to carry a winding package core, means for moving the units in a path of elongated shape including a straight portion of substantial length, a mechanical driving element extending along said straight portion of path, means on the several units for transmitting driving force from the said mechanical driving element to the winding package on the unit thereby to rotate the winding package during its travel, means operative during the winding to distribute the strand in conical layers of less length than the finished package length, and means for shifting the ranges of strand traverse axially of the packages.

2. A traveling unit winding machine having therein a plurality of flexibly connected winding units each adapted to carry a winding package core, means for moving the units in a path of elongated shape including a straight portion of substantial length, a non-traveling rotary tractor roll extending along said straight portion of path, means on the several units for transmitting driving force from the said tractor roll to the winding package on the unit thereby to rotate the winding package during its travel, means operative during the winding to distribute the strand in conical layers of less length than the finished package length, and means for shifting the ranges of strand traverse axially of the packages.

3. A traveling unit winding machine having therein a plurality of flexibly connected winding units each adapted to carry a winding package core, means for moving the units in a path of elongated shape including a straight portion of

substantial length, a non-traveling rotary tractor roll extending along said straight portion of path, a tire on each unit adapted to contact with and be driven by said tractor roll and a connection from said tire to the winding package for rotating the winding package during its travel, means operative during the winding to distribute the strand in conical layers of less length than the finished package length, and means for shifting the ranges of strand traverse axially of the packages.

4. A traveling unit winding machine having therein a plurality of flexibly connected winding units each adapted to carry a winding package core, means for moving the units in a path of elongated shape including a straight portion of substantial length, a belt running along said straight portion of travel, means on the several units for transmitting driving force from the said belt to the winding package on the unit thereby to rotate the winding package during its travel, means operative during the winding to distribute the strand in conical layers of less length than the finished package length, and means for shifting the ranges of strand traverse axially of the packages.

5. A traveling unit winding machine having therein a plurality of flexibly connected winding units each adapted to carry a winding package core, means for moving the units in a path of elongated shape including a straight portion of substantial length, a belt running along said straight portion of travel, a pulley on each unit adapted to contact with and be driven by said belt and a connection from said pulley to the winding package for rotating the winding package during its travel, means operative during the winding to distribute the strand in conical layers of less length than the finished package length, and means for shifting the ranges of strand traverse axially of the packages.

6. A traveling unit winding machine having therein a plurality of flexibly connected winding units each adapted to carry a winding package core, means for moving the units in a path of elongated shape including a straight portion of substantial length, a mechanical driving element extending along said straight portion of path, the several winding units having their winding package cores disposed transversely to the said mechanical driving element, means on the several units for transmitting driving force from the said mechanical driving element to the winding package on the unit thereby to rotate the winding package during its travel, means operative during the winding to distribute the strand in conical layers of less length than the finished package length, and means for shifting the ranges of strand traverse axially of the package.

7. A traveling unit winding machine having therein a plurality of winding units, means for moving the units in a procession during winding, a rotary tractor roll extending along the path of travel of the units, means on the several units for holding winding package cores transversely with respect to the tractor roll, and means on the several units for transmitting driving force from the said tractor roll to the winding packages thus transversely related to the tractor roll.

8. A traveling unit winding machine having therein a plurality of winding units, means for moving the units in a procession during winding, a mechanical driving element extending along the path of travel of the units, means on the several units for holding winding package cores

transversely with respect to the mechanical driving element, traverse means on the several units arranged to move generally axially along the winding package core and including means for progressively shifting the range of the traversing movement, and means on the several units for transmitting driving force from the said mechanical driving element to the winding package.

9. A traveling unit winding machine having therein a plurality of winding units, means for moving the units in a procession during winding, a rotary tractor roll extending along the path of travel of the units, means on the several units for holding winding package cores transversely with respect to the said tractor roll, traverse means on the several units arranged to move generally axially along the winding package core, and means on the several units for transmitting driving force from the said tractor roll to the winding package.

10. A traveling unit winding machine having therein a plurality of winding units, means for moving the units in a procession during winding, a mechanical driving element extending along the path of travel of the units, means on the several units for holding winding package cores transversely with respect to the mechanical driving element, traverse means on the several units arranged to move generally axially along the winding package core and including means for progressively shifting the range of the traversing movement, and means on the several units for transmitting driving force from the said mechanical driving element to the winding package and to the traverse means.

11. A traveling unit winding machine having therein a plurality of winding units, means for moving the units in a procession during winding, a mechanical driving element extending along the path of travel of the units, means on the several units for holding winding package cores transversely with respect to the mechanical driving element, traverse means on the several units driven frictionally from their respective winding packages, and means on the several units for transmitting driving force from the said mechanical driving element to the winding package.

12. A traveling unit winding machine having therein a plurality of winding units, means for moving the units in a procession during winding, a mechanical driving element extending along the path of travel of the units, means on the several units for holding winding package cores transversely with respect to the mechanical driving element, traverse means on the several units arranged to move generally axially along the winding package core, and means on the several units for transmitting driving force from the said mechanical driving element to the winding package and for imparting to the traverse means a traversing movement less in length than the package length.

13. A traveling unit winding machine having therein a plurality of winding units, means for moving the units in a procession during winding, a mechanical driving element extending along the path of travel of the units, means on the several units for holding winding package cores transversely with respect to the mechanical driving element, traverse means on the several units arranged to move generally axially along the winding package core, and means on the several units for transmitting driving force from

the said mechanical driving element to the winding package and for imparting to the traverse means a traversing movement less in length than the package length, the traverse means including means for progressively shifting the range of said traversing movement.

14. A traveling unit winding machine having therein a plurality of winding units, means for moving the units in a procession during winding,

10 a mechanical driving element extending along the path of travel of the units, means on the several units for holding winding package cores transversely with respect to the mechanical driving element, traverse means on the several units arranged to move generally axially along the winding package core, means on the several units for transmitting driving force from the said mechanical driving element to the winding package and for imparting to the traverse means a traversing movement less in length than the package length, and means controlled by the growth of the winding package for progressively shifting the range of said traversing movement.

15. A traveling unit winding machine having therein a plurality of winding units, means for moving the units in a procession during winding, a rotary tractor roll extending along the path of travel of the winding units, rotatable means on the several units arranged to hold winding package cores transversely with respect to the tractor roll, a tire on each unit contacting with and driven by the tractor roll, and a connection including bevel gearing between the tire and said rotatable core-holding means.

16. A traveling unit winding machine having therein a plurality of winding units, means for moving the units in a procession during winding, a rotary tractor roll extending along the path of travel of the units, rotatable means on the several units arranged to hold winding package cores transversely with respect to the tractor roll, and a rotatable beveled friction element connected to the rotatable core-holding means and frictionally contacting with the tractor roll.

17. A traveling unit winding machine having therein a plurality of winding units, means for moving the units in a procession during winding, a rotary tractor roll extending along the path of travel of the units, each unit being arranged to hold a winding package core transversely with respect to the tractor roll, yarn-traversing means on each unit adapted to distribute the winding yarn on the said transversely disposed package core, and a rotatable beveled friction element connected to the traversing means and frictionally contacting the tractor roll.

18. A traveling unit winding machine having therein a plurality of winding units, means for moving the units in a procession during winding, a rotary tractor roll extending along the path of travel of the units, and yarn-traversing means on each unit comprising a cam, a traversing yarn guide, a rotatable beveled friction element connected to the cam and frictionally contacting the tractor roll, and means for progressively shifting the range of traversing movement of the guide along the length of the winding package.

19. A traveling unit winding machine having therein a plurality of winding units, means for moving the units in a procession during winding, a rotary tractor roll extending along the path of travel of the winding units, rotatable means on the several units arranged to hold winding

package cores transversely with respect to the tractor roll, yarn-traversing means on each unit, and each unit including two rotatable beveled friction elements frictionally contacting with the tractor roll and connected to drive the winding package and the traversing means respectively.

20. A traveling unit winding machine having therein a plurality of winding units, means for moving the units in a procession during winding, a rotary tractor roll extending along the path of travel of the units, rotatable means on the several units arranged to hold winding package cores, yarn-traversing means on each unit, and each unit including two rotatable beveled friction elements frictionally contacting with the tractor roll and connected to drive the winding package and traversing means respectively, the winding package and the path of traverse of the traversing means of each unit being disposed at an acute angle to the tractor roll.

21. A traveling unit winding machine having therein a plurality of winding units, means for moving the units in a procession during winding, a rotary tractor roll extending along the path of travel of the units, means on the several units arranged to hold winding package cores, means for driving the winding packages from the tractor roll, and each unit including a rotatable element arranged to contact with a conical growing face of the winding package, and yarn-traversing means associated with and operated by the said rotatable element.

22. A traveling unit winding machine having therein a plurality of winding units, means for moving the units in a procession during winding, a rotary tractor roll extending along the path of travel of the units, means on the several units arranged to hold winding package cores, means for driving the winding packages from the tractor roll, and each unit including a slidable bracket and a rotatable element on said bracket and arranged to contact with a conical growing face of the winding package, and yarn-traversing means associated with and operated by the said rotatable element.

23. A traveling unit winding machine having therein a plurality of winding units, means for moving the units in a procession during winding, a rotary tractor roll extending along the path of travel of the units, means on the several units arranged to hold winding package cores, means for driving the winding packages from the tractor roll, and each unit including a grooved conical roll disposed to contact with and be driven by a conical growing face of the winding package to distribute the winding yarn thereon.

24. A traveling unit winding machine having

therein a plurality of winding units, means for moving the units in a procession during winding, means for rotating the winding packages of the several units, and a non-traveling yarn guide cooperating with the winding yarns of a plurality of the units, said yarn guide having an inclination such as to cause the winding yarn to traverse slowly from one end of the winding package to the other and having a short supplemental motion such as to traverse the winding yarn back and forth across a conical growing face of the winding package.

25. A traveling unit winding machine having therein a plurality of winding units each having means for holding a winding package in a vertical position, means for moving the units in a procession during winding, means for rotating the winding packages of the several units, and a non-traveling yarn guide cooperating with the 20 winding yarns of a plurality of the units, said yarn guide having a vertical inclination such as to cause the winding yarn to traverse slowly from one end of the winding package to the other and having a short supplemental vertical motion such as to traverse 25 the winding yarn back and forth across a conical growing face of the winding package.

26. A traveling unit winding machine having therein a plurality of winding units each having means for holding a winding package in a vertical position, means for moving the units in a procession during winding, means for rotating the winding packages of the several units, and a non-traveling rod cooperating with the winding 30 yarns of a plurality of the units, said rod having a vertical inclination such as to cause the winding yarn to traverse slowly from one end of the winding package to the other and having a short supplemental vertical motion such as to traverse 35 the winding yarn back and forth across a conical growing face of the winding package.

27. A traveling unit winding machine having therein a plurality of winding units, means for moving the units in a procession during winding, 45 means including a belt running along the path of travel of the units for rotating the winding packages of the several units, and a non-traveling yarn guide cooperating with the winding yarns of a plurality of the units, said yarn guide 50 having an inclination such as to cause the winding yarn to traverse slowly from one end of the winding package to the other and having a short supplemental motion such as to traverse the winding yarn back and forth across a conical 55 growing face of the winding package.

EDWARD J. ABBOTT.
